UNITED STATES PATENT OFFICE.

SAMUEL L. ALLEN, OF MOORESTOWN, NEW JERSEY

RUNNER FOR SLEDS.

No. 797,838.

Specification of Letters Patent.

Patented Aug. 15, 1905.

Application filed March 2, 1905. Serial No. 248,060.

To all whom it may concern:

Be it known that I, SAMUEL L. ALLEN, a citizen of the United States, and a resident of Moorestown, county of Burlington, State of New Jersey, have invented certain new and useful Improvements in Runners for Sleds, of which the following is a full, clear, and complete disclosure.

The object of my invention is to produce an improved runner for sleds of the class in which is employed a laterally-bendable side frame or runner for guidance of the sled, means being connected with the body of the sled and the runner for bending the same.

The improved features of this sled are particularly applicable to sleds made similar to that of my prior patent, No. 408,681, issued August 13, 1889.

In the use of sleds having laterally-bendable runners the sled is guided by reason of the fact that the runners may be made to form a curve, and therefore impress in the snow or ice curved tracks which the runners must follow and by which they are guided, thereby directing the path of the sled. In the course of my improvements in this class of sleds I have found that the greater the amount of the bearing-surface of the runner or runners that is capable of being bent laterally the more accurately and surely will the sled be guided that is to say, the more nearly the length of the runners conforms to the arc of a circle when bent laterally the more accurately will the runners fit or register with the tracks made, and the sled will therefore be guided more easily and surely.

The object, therefore, of the present invention is to increase the percentage of the bearing portion of the runners that is bent laterally without interfering with their strength or rigidity as a supporting means for the body of a sled.

Briefly, my invention comprises the arrangement of the runners of a sled so that the extent of the bearing portion is brought considerably ahead of the forward support of the body of the sled and also so that the runners may be allowed to bend for a considerable distance to the rear of the forward support of the sled. The details of this arrangement will be more particularly described in the following specification and pointed out in the accompanying claims.

For a full, clear, and exact description of this form of my invention reference may be had to the following specification and to the accompanying drawings, forming a part thereof, in which—

Figure 1 represents a bottom plan view of a sled embodying my improvements. Fig. 2 is a side elevation thereof, and Fig. 3 is a cross-section of one runner.

Referring to said drawings, the numeral 1 indicates the top or body portion of the sled, which is composed of longitudinal slats or strips 2, said slats being held together by transverse benches or cleats 3 and 4, to which said slats are nailed or otherwise secured, as indicated at 5. Connected to the ends of benches 3 and 4 are side rails or bars 6, which extend the entire length of the sled and which are connected at their forward ends by means of a transverse bar 7. Said longitudinal bars or rails 6 are pivoted, as at 8, to a third transverse cleat 9, said cleat being unconnected with the slats 2, which form the top of the sled, said slats being allowed merely to rest upon the upper side of said cleat 9. The runners 10 are connected at their forward upturned ends with longitudinal bars 6 and are held in the correct relation to said bars by a series of legs or braces 11 and 12. The runners 10 are preferably made in the form of angle irons or bars having an inverted-T-shaped cross-section.

To the center of the forward cross-bar 7 is pivoted a lever 13, the ends of which project beyond the sides of the sled and are adapted to be engaged by the hands or feet of the person riding upon the sled and also by means of ropes attached to ends of the bar. Rigidly connected with said lever 13 and extending rearwardly to pivotally engage the central slat of the top 1 of the sled is a link or bar 14, in this instance consisting of two parallel strips, said strips being pivoted to the top 1 by means of a rivet or other device 15. It will now be seen that in order to guide the sled to the right the right end of the lever is drawn back just as in guiding a horse, and vice versa, or if the feet are used one end or the other of the lever 13 is pressed forward by the foot as required, thereby moving the cross-bar 7 longitudinally and so bending the runners 10 and the side bars or rails 6 in the same direction. This will cause the sled to follow a curved path toward one side or the other, according to which end of the lever 13 is pressed upon.

Heretofore in the manufacture of these sleds the runner has been caused to bend upwardly from about the point of connection

with the forward braces or supports 12 to the point where the same are connected with the side bars or rails 6. This has confined the bearing portion to the length of the runner which is to the rear of said braces, and therefore somewhat limited the lateral curve of the runner which is in contact with the ground when bent laterally. In the present form of my invention the runner does not commence to bend upwardly to meet the side bars until substantially the point indicated by A in the figures of the drawings is reached, from which point the runners then bend upwardly in a gradual curve for slightly over half the height of the sled, at which point a sharp bend is made, as indicated at 16, so that the runner extends slightly rearward and then is bent forward, as indicated at 17, for attachment to the side bars or rails 6. This construction gives a much greater per cent. of the total length of sled as bearing-surface for contact with the snow or ice and at the same time does not give too great or abrupt curve to the forward portion of the runners which are connected with the body of the sled. This may be illustrated in the following way: Taking, for instance, a sled in which the total length of each runner is thirty-six inches, the bearing-surface at the rear of the forward, supports in the previous forms of sleds having bendable runners amounted only to about twenty-one and one-half inches, whereas in the form of sled herein described the bearing-surface has been extended to approximately twenty-eight inches. Furthermore, in the previous designs of sleds of this character the length of the flexible portion which is in contact with the snow or ice amounted only to about nine inches, whereas in the present form the bearing portion which may be laterally bent is substantially sixteen inches or that indicated between the lines A and B in the drawings. It will therefore be seen that by this construction not only is a greater bearing-surface given to the runner, which will prevent the same from sinking into the snow to such an extent as heretofore, but also that the bearing portion of the runner which is in contact with the ice or snow is made bendable for a much greater portion of its length, and therefore more nearly conforms to the arc of a circle which the whole runner should assume in order to theoretically cause the sled to traverse exactly a curved path.

It will be seen that various changes may be made in the form, arrangement, and proportion of the parts of the construction herein described without departing from the spirit and scope of my invention; but

What I claim, and desire to protect by Letters Patent of the United States, is—

1. In a sled having flexible runners, a run-

ner which curves gradually upward from a point intermediate the forward runner-support and the forward end of the sled providing a maximum bearing-surface for the flexible portion, substantially as described.

2. In a sled having flexible runners, a runner which curves gradually upward from a point intermediate the forward runner-support and the forward end of the sled, and then sharply rearwardly to connect with the body of the sled, thereby providing a maximum bearing-surface for the flexible portion, substantially as described.

3. In a sled having flexible runners, forward supports which are movably related to the forward portion of the body of the sled, the runners of said sled being curved gradually upward from a point intermediate said forward supports and the forward end of the sled, and therefrom being sharply curved to connect with the forward end of the body of the sled.

4. In a sled having flexible runners, forward supports which are adapted to move transversely in relation to the body of the sled, the runners of said sled being curved gradually upward from a point intermediate said forward supports and the forward end of the sled, and then being curved rearwardly and connected with the body of the sled, thereby providing a maximum bearing-surface for the flexible portion and allowing the runner to curve transversely to a point in the rear of said forward support.

5. In combination with a sled having flexible runners, a runner T-shaped in cross-section which curves gradually upward from a point intermediate the forward runner-support and the forward end of the sled providing a maximum bearing-surface for the flexible portion, substantially as described.

6. In combination with a sled having flexible runners, a runner T-shaped in cross-section, forward supports which are adapted to move transversely in relation to the body of the sled, the runners of said sled being curved gradually upward from a point intermediate said forward support and the forward end of the sled, and then being curved rearwardly and connected with the body of the sled, thereby providing a maximum bearing-surface for the flexible portion, and allowing the runner to curve transversely to a point in the rear of said forward support.

In witness whereof I have hereunto set my hand this 1st day of March, 1905.

SAMUEL L. ALLEN.
